UNITED STATES PATENT OFFICE.

HARDEN PALMER, OF EVERETT, MASSACHUSETTS.

SHUTTER-WORKER.

SPECIFICATION forming part of Letters Patent No. 324,149, dated August 11, 1885.

Application filed November 17, 1884. (No model.)

To all whom it may concern:

Be it known that I, HARDEN PALMER, of Everett, county of Middlesex, and State of Massachusetts, have invented an Improvement 5 in Shutter-Operators, of which the following description, in connection with the accompanying drawings, is a specification, like letters on the drawings representing like parts.

10 This invention relates to shutter-workers; and it has for its object to improve, simplify, and cheapen the construction.

The invention consists in the construction hereinafter particularly described, and pointed 15 out in the claim.

Figure 1 represents in elevation a window having usual blinds or shutters provided with my improved shutter-operator; Fig. 2, a section of Fig. 1 on the dotted line *x x*; Fig. 3, a 20 section of the shutter-operator, taken on the dotted line *y y*; Fig. 4, the shaft being shown in elevation. Fig. 4 shows in elevation the bent lever and its operating mechanism as viewed from the dotted line *z z*; Fig. 3, the 25 bent lever being, however, turned to the right.

The window-jamb *A*, sill *B*, and blinds or shutters *C*, pivoted to the jamb *A* by hinges *D*, are and may be of any ordinary construction, so need not be herein described.

30 The box or casing *a*, of sufficient size to contain the operating parts, is secured, as shown, in this instance beneath the sill *B*.

One end of the rod or shaft *b*, having the worm *d* attached to it, has its bearings at 2 35 in the box *a*, the said rod being of sufficient length to extend entirely through the side of the building, such rod at its inner side, within the building, being provided with a handle, *b'*, and knob *b''*.

40 One end of the bent lever *c*, which is employed to operate the shutter, is extended through the worm-gear *e*, placed in the case *a* at right angles to the worm, and the said lever at each end of the worm-gear takes bearing in the said case. The upturned outer 45 end of the lever *c* enters a slot in the lower end of the blind or shutter or in a metal plate connected therewith.

To open or close the shutter by means of 50 the apparatus herein described, it is only necessary to turn the crank *b'* and rotate the rod

or shaft *b*, thus operating the bent lever *c* by means of the gearing between them, the movement of the bent lever enabling the blind or shutter to be placed and held at any desired 55 point.

The device herein described is simple and efficient, and may be applied to any shutter with greater facility than those heretofore known to me, and all the working parts being 60 contained within the box derangement caused by the action of the weather, &c., is entirely avoided.

I design my shutter-worker for application more specially to frame houses, and so construct it as to obviate cutting or mortising the sill or other part of the window-frame. The box containing the gearing is applied exteriorly of the building, beneath the sill, and the rods *b* and *c* are put in place through auger-holes; and I do not claim, broadly, the combination of worm-gearing arranged in a case 70 and connected by a bent arm with the shutter, and operated through the gearing by a shaft extending through the side of the house into 75 such house.

I am aware that a shutter having a rod attached to the casing, and upon which slides a sleeve pivoted to an arm secured to the axis of a worm-gear seated in a recess in a window-sill and turned by a worm, has been employed; 80 but such construction I do not herein claim.

I claim—

The casing or box *a*, secured exteriorly of the building beneath the sill *B*, and containing 85 the vertical worm-wheel *e* and meshing worm-gear *d*, combined with the bent lever *c*, having bearings in the casing or box, and engaged by the worm-wheel, and connected to or with the shutter, and the rod or shaft *b*, extended 90 through the side of the house and having bearings in the casing or box and engaging the worm to operate it, all constructed and arranged substantially as shown and described.

In testimony whereof I have signed my name 95 to this specification in the presence of two subscribing witnesses.

HARDEN PALMER.
